[57] CLAIM

The ornamental design for a cord leader, substantially as shown and described.

DESCRIPTION

FIG. 1 is a top plan view of a cord leader showing my new design;

FIG. 2 is a top plan view thereof;

FIG. 3 is a bottom plan view thereof;

FIG. 4 is an end elevational view taken from the left side of FIG. 1;

FIG. 5 is an end elevational view taken from the right side of FIG. 1; and

FIG. 6 is a sectional view taken on line 6—6 in FIG. 1.
